(57) **CLAIM**

The ornamental design for a plastic produce container, as shown and described.

DESCRIPTION

FIG. 1 is a top perspective view of a plastic produce container according to the present invention;

FIG. 2 is a bottom perspective view of the container of FIG. 1. The oval-shaped, broken line of FIG. 2 defines the bounds of the claimed design and forms no part thereof;

FIG. 3 is a front side elevational view of the container shown in FIG. 1;

FIG. 4 is a rear side elevational view of the container shown in FIG. 1;

FIG. 5 is a left side elevational view of the container shown in FIG. 1;

FIG. 6 is a right side elevational view of the container shown in FIG. 1;

FIG. 7 is a top plan view of the container shown in FIG. 1. The oval-shaped, broken line of FIG. 7 defines the bounds of the claimed design and forms no part thereof; and,
FIG. 8 is a bottom plan view of the container shown in FIG. 1. The oval-shaped, broken line of FIG. 8 defines the bounds of the claimed design and forms no part thereof.

1 Claim, 7 Drawing Sheets
